PORTABLE COLLAPSIBLE CRANE

Henry D. Rogers, Richmond, Calif.

Application August 15, 1938, Serial No. 224,955

14 Claims. (CL. 212—140)

This invention relates to a portable collapsible crane.

The heavy duty crane is indispensable wherever construction work is in progress, where a dam is being built, a bridge is being erected, a large diameter pipe line is being laid, heavy machinery is being removed or installed, etc. A large heavy duty crane is usually shipped on flatcars or heavy trucks to the site where it is to be used, and is there erected for the particular work in hand. It must be taken down when the work is completed or for transportation to another place.

The object of this invention is generally to improve the construction and operation of heavy duty cranes; to provide a crane which is wheel supported and adapted to be hauled by a tractor from place to place; to provide a crane having a triangularly-shaped base frame with a tongue for connection with a tractor at one end, and supported by wheels at the opposite end; to provide a triangularly-shaped boom frame which is pivotally supported over the wheels of the base frame and which may be raised from a horizontal trailing position with relation to the base frame to a vertical position for use; to provide a frame structure both for the base and for the boom which has pivotal connections at certain points, permitting the frame members to be brought together in substantial parallelism, or in other words materially contracted, for hauling over highways; and to provide a frame structure which may be completely taken apart for shipment on flatcars or trucks, and in which the frame members may be telescoped with relation to each other to consume as little longitudinal space as possible.

The crane is shown by way of illustration in the accompanying drawings, in which

Fig. 1 is a side elevation of the crane showing it erected for use;

Fig. 2 is a plan view of the base frame of the crane, showing the boom frame removed;

Fig. 3 is a rear view of the boom frame in erected position;

Fig. 4 is a perspective view of one of the wheel supported carriages;

Fig. 5 is a side elevation of the crane showing the boom frame lowered for transportation; and

Fig. 6 is a plan view of the crane showing it contracted to permit it to be hauled over narrow roads and highways.

Referring to the drawings in detail, and particularly to Figs. 1 to 4, A indicates in general a base frame, and B a boom frame. The base frame is best shown in Figs. 1 and 2. It con-

sists of a drawhead 2 to which is pivotally attached as at 3—3 a pair of rearwardly extending arms 4—4. The drawhead is adapted to be attached to and supported by a tractor such as shown at C, while the rear ends of the arms 4 are attached to a pair of wheel-supported carriages D—D. These carriages are identical in construction, and are best shown in Figs. 3 and 4. Each carriage consists of a horizontal frame 5 constructed in any suitable manner. At the opposite ends are secured two downwardly extending frames or brackets 6—6, between which is secured a shaft or axle 7 on which are journaled three or more wheels 8. At the inner end of the frame 5 and bracket 6 is a flange or plate 9, the function of which will hereinafter be described. At the top of the frame are two upwardly extending lugs 10, and at the rear of the flange 9 and the frame 5 is a fork-shaped bracket 11 which is braced with relation to the frame by a plate 12. The rear ends of the base frame arms 4 fit between the forks 11, and pins 14 extend therethrough to form a pivotal connection between the carriages and the arms 4.

The boom frame B consists of a pair of leg members 15—15 pivotally secured at their upper ends as at 6 to a sheave head 16. The lower ends of the boom legs are pivotally supported as at 17—17 between fork-shaped members 18—18, which in turn are pivotally supported between the lugs 10—10. The pivotal connections 17 permit spreading of the lower ends of the leg members 15, and the pivotal connections formed between the lugs 10—10 permit vertical swinging movement to raise or lower the boom frame, as will hereinafter be described.

The crane here illustrated is built so that it may be pulled from place to place by the tractor. If the crane has been erected and the work performed has been on comparatively open or unobstructed land, the crane may be hauled about without taking it down; on the other hand, if it is to be hauled over the highway to another location, it becomes essential to lower the boom frame from its vertical position to a horizontal position such as shown in Fig. 6, so as to clear bridges, overhead wires, and the like, and it also becomes necessary to contract both the base and boom frames so that the entire structure will be sufficiently narrow to permit hauling it over highways without obstructing traffic.

With the crane erected as shown in Fig. 1, it becomes possible to raise and lower loads by means of the hook shown at 20, as the hook is provided with a sheave 21, and a similar sheave 23

22 is journaled on the sheave head 16. The usual type of cable 23 is reeved through the sheave blocks 21 and 22, and is extended to a drum 24 mounted on and driven by the tractor. 5 The boom may assume any position between the vertical position shown in Fig. 1 and the horizontal position shown in Fig. 6, the position being controlled by a cable 25 operated by a drum 26 mounted on and driven by the tractor. This 10 cable passes over sheave blocks 27 and 28, and one end is anchored as at 29. By paying out on the cable 25, the boom is lowered or swung about the pivotal lugs 10 on the respective carriages to any position desired, while by applying power to 15 the drum 26 and hauling on the cable it may be raised. The boom legs 15, the wheel-supported carriages D—D, and the arms 4—4 of the base frame normally assume their spread position shown in Figs. 2 and 3, when the boom is erected 20 for use. To prevent contraction of the arms of the base frame during operation, a cross-beam 30 is bolted between the flanges 8—9 of the carriages D, and extra cross-braces may be bolted between the arms as shown at 31 and 32. Similar 25 cross-braces 33 and 34 are also secured between the legs of the boom, and a rigid structure is thus provided, each frame being substantially triangular in shape and presenting the widest support at the point where the heaviest 30 load is applied.

When the boom B is swung from horizontal to upright position as shown in Fig. 1, means must be provided to prevent the boom from swinging beyond vertical position, as it would otherwise 35 swing about the pivotal lugs 10—10 and fall back on the base frame and tractor, and completely wreck the entire structure. To prevent this, stop arms 35 are pivotally secured to the boom legs 15 as shown at 36. The lower ends 40 of the arms slide in channel-shaped track members 37 pivotally secured as at 38 to the base frame arms 4. The outer ends of said track members are supported by and secured to the cross-brace 31. A shoulder 39 is formed at the inner 45 end of each track member; hence as the boom is being raised, and the lower ends of the arms 35 slide rearwardly on the tracks 37, a point will finally be reached when they engage the shoulders 39, and further movement of the 50 boom is stopped, thus preventing movement of the boom beyond a vertical position. There is a double swivel connection between the upper ends of the arms 35 and the boom legs 15, so as to permit them to be moved into parallelism with 55 the legs 15.

If the boom is to be lowered and transported to another site, and particularly if it is to be hauled over a highway by means of the tractor, a frame such as shown at 42 will first be placed 60 on the cross-bar 30 and there secured. This frame carries a wide roller 43 at its upper end, which will receive the cables 23 and 25 as the boom frame is being lowered. The boom frame, as previously stated, is lowered by merely paying out on the cable 25, and as it lowers, the cables will finally rest on the roller 43 in a manner similar to the cable support shown in Fig. 5. The support there shown is another support 65 which will hereinafter be described.

70 After the boom has been lowered to horizontal position, a dolly or similar support will be placed under the sheave head, and the cables which lower the boom will be slackened to remove the strain. The several cross-beams 30, 31, 32 33 75 and 34 are then unbolted and removed. A pair

of chains such as shown at 44 are then connected between the outer ends of the carriages and the adjacent ends of the arms 4. There is a turn-buckle 45 intermediate the ends of each chain, and these turn-buckles are tightened so 5 as to swing the carriages about the pivots 14 just a sufficient amount to cause the wheels 8 to toe inwardly, then by hauling the entire structure in a forward direction by means of the tractor, each carriage will tend to move inwardly and swing the arms 4—4 about their pivots 3—3, and the boom legs 15—15 about their pivots 6, until they assume a substantially parallel position such as shown in Fig. 5. At this point the turn-buckles are released and the 10 chains are changed from the first position to the second position indicated at 50; that is, they are hooked to the lower ends of the boom legs. The turn-buckles are again tightened to swing the carriages back to normal position, or at right 20 angles to the longitudinal axis of the frames A and B, and after the carriages have been straightened out, the chains are again hooked to the inner ends of the arms 4, or returned to their original position where they remain 25 during the towing or hauling operation. This connection is essential, particularly when towing, as it reduces swinging movement of the carriages about the pivots 14. When the frame arms and boom legs have been brought together 30 as shown in Fig. 6, a pair of stanchions 52 permanently secured at the rear ends of the arms 4—4 are connected by a cross-shaft and a roller such as shown at 53. The cables are passed over 35 this roller and a strain is put on the cable 25 sufficient to hold the boom in a horizontal position without any support under the sheave head. In this position the entire crane may be hauled over a highway, as its normal width has been reduced to a minimum and is such that ample 40 clearance is given for traffic.

When the crane reaches its new destination, the turn-buckles on the chains 44 are again tightened to toe in the wheels. The tractor is now backed up and as the wheels assume a 45 slight angle with relation to the longitudinal axis of the frame arms and boom legs, they will gradually cause spreading movement of the carriages and the arms and boom legs connected therewith, it being understood that a wheel-supported dolly or the like is placed under the sheave head during such movement. When they have been spread apart a proper distance, the cross-brace 30 is bolted into position between the carriages, and so are the braces 31 and 32, 55 and the bars 33 and 34 are similarly bolted between the boom legs. The frame 42 is again placed on the cross-brace 30, and the cables placed over the roller 43. The strain is then put on the cable 25 by applying power to the 60 drum 26, and the boom is raised to any position desired. The frame 42 may remain in position at all times except when the base is contracted to assume the position shown in Fig. 6. During hauling of the crane, the brace members 65 30 to 34 may be placed on a heavy truck, and so may the frame 42, as these are the only parts which are detached.

If the crane as a whole is to be shipped a considerable distance, for instance on heavy trucks 70 or on flatcars, it is possible to disconnect it completely. By removing the pivot pins 3, the draw-head 2 may be removed. All the cross-braces 30 to 34 may be removed as previously described; the carriages may be separated from the arms 75

4 by removing the pivot pins 14; and the arms 4 may themselves be separated by unbolting them at the points indicated at 60. The arms may be box girders, and as such are hollow, and 5 as the forward ends of the arms 4 are smaller than their rear portions, it is possible to slip the smallest sections within the larger sections so as to reduce longitudinal space. The boom itself may be similarly taken apart. Plainly speaking, 10 the entire crane is constructed of parts which may be quickly taken apart or assembled, and which may be stored or piled in comparatively little space during transportation.

Having thus described and illustrated my invention, what I claim and desire to secure by Letters Patent is:

1. A portable collapsible crane comprising a pair of wheel-supported carriages, a base frame supported at its rear end by said carriages, means 20 for attaching and supporting the front end of the base frame to a tractor, a boom frame supported by the carriages, and pivotal connections between the carriages and the respective frames to permit lateral movement of the carriages in 25 opposite directions to simultaneously contract or spread the rear end of the base frame and the lower end of the boom frame.

2. A portable collapsible crane comprising a pair of wheel-supported carriages, a base frame 30 supported at its rear end by said carriages, means for attaching and supporting the front end of the base frame to a tractor, a boom frame supported by the carriages, pivotal connections between the base frame and the respective carriages, pivotal connections between the boom frame and the respective carriages, and means 35 for imparting lateral movement to the carriages in opposite directions to simultaneously widen or narrow the space between the ends of the base frame and the boom frame which are pivotally attached to the carriages.

3. A portable collapsible crane comprising a pair of wheel-supported carriages, a base frame supported at its rear end by said carriages, means 45 for attaching and supporting the front end of the base frame to a tractor, a boom frame supported by the carriages, pivotal connections between the base frame and the respective carriages, pivotal connections between the boom frame and the respective carriages, means for imparting lateral movement to the carriages to 50 simultaneously widen or narrow the space between the ends of the base frame and the boom frame which are pivotally attached to the carriages, and a second pivotal connection between the boom frame and the respective carriages to permit vertical swinging movement of the boom frame with relation to the base frame.

4. A portable collapsible crane comprising a 60 pair of wheel-supported carriages, a base frame supported at its rear end by said carriages, means for attaching and supporting the front end of the base frame to a tractor, a boom frame supported by the carriages, pivotal connections between 65 the base frame and the respective carriages, pivotal connections between the boom frame and the respective carriages, means for imparting lateral movement to the carriages to widen or narrow the space between the ends of 70 the frames which are pivotally attached to the carriages, a second pivotal connection between the boom frame and the respective carriages, and means for swinging the boom frame about said second pivotal connection from a horizontal 75 trailing position with relation to the base frame

to a vertical position, or to any intermediate point.

5. A portable collapsible crane comprising a pair of wheel-supported carriages, a base frame supported at its rear end by said carriages, means 5 for attaching and supporting the front end of the base frame to a tractor, a boom frame supported by the carriages, pivotal connections between the base frame and the respective carriages, pivotal connections between the boom 10 frame and the respective carriages, means for imparting lateral movement to the carriages to widen or narrow the space between the ends of the frames which are pivotally attached to the carriages, a second pivotal connection between 15 the boom frame and the respective carriages, means for swinging the boom frame about said second pivotal connection from a horizontal trailing position with relation to the base frame to a vertical position, or to any intermediate point, 20 and means for stopping swinging movement of the boom frame beyond a vertical position.

6. A portable collapsible crane comprising a pair of wheel-supported carriages, a boom frame comprising a pair of boom legs supported and 25 connected at their lower ends one to each carriage, said connections permitting both horizontal and vertical pivotal movement of the legs with relation to the carriages, a sheave head pivotally connecting the upper ends of the boom legs, a 30 base frame comprising a pair of arms supported and pivotally connected at their rear ends one to each carriage, a drawhead pivotally connecting the forward ends of said arms, said drawhead adapted to be connected to and supported 35 by a tractor, said carriages being laterally movable to spread the lower ends of the boom legs and the rear ends of the base frame arms, and means for securing the carriage against lateral movement when a predetermined spread 40 is reached.

7. A portable collapsible frame comprising a pair of wheel-supported carriages, a boom frame comprising a pair of boom legs supported and 45 connected at their lower ends one to each carriage, said connections permitting both horizontal and vertical pivotal movement of the legs with relation to the carriages, a sheave head pivotally connecting the upper ends of the boom legs, a base frame comprising a pair of arms 50 supported and pivotally connected at their rear ends one to each carriage, a drawhead pivotally connecting the forward ends of said arms, said drawhead adapted to be connected to and supported by a tractor, said carriages being laterally movable to spread the lower ends of the boom legs and the rear ends of the base frame arms, means for securing the carriages against 55 lateral movement when a predetermined spread is reached, and means for supporting and swinging the boom legs and sheave head from a horizontal trailing position with relation to the base frame to a vertical position, or to any intermediate position.

8. A portable collapsible crane comprising a 65 pair of wheel-supported carriages, a boom frame comprising a pair of boom legs supported and connected at their lower ends one to each carriage, said connections permitting both horizontal and vertical pivotal movement of the legs with 70 relation to the carriages, a sheave head pivotally connecting the upper ends of the boom legs, a base frame comprising a pair of arms supported and pivotally connected at their rear ends one to each carriage, a drawhead pivotally connecting 75

the forward ends of said arms, said drawhead adapted to be connected to and supported by a tractor, said carriages, together with the boom legs and base frame arms, adapted to assume a position parallel and in substantial contact with each other, means for imparting lateral movement to the carriages to spread the lower ends of the boom legs and the rear ends of the base frame arms, and means for securing the carriages against lateral movement when a predetermined spread is reached.

9. A portable collapsible crane comprising a pair of wheel-supported carriages, a boom frame comprising a pair of boom legs supported and connected at their lower ends one to each carriage, said connections permitting both horizontal and vertical pivotal movement of the legs with relation to the carriages, a sheave head pivotally connecting the upper ends of the boom legs, 20 a base frame comprising a pair of arms supported and pivotally connected at their rear ends one to each carriage, a drawhead pivotally connecting the forward ends of said arms, said drawhead adapted to be connected to and supported by a tractor, said carriages, together with the boom legs and base frame arms, adapted to assume a position parallel and in substantial contact with each other, the wheels on said carriages being also parallel to the boom legs and the base frame 30 arms, means for swinging the carriages with relation to the base frame arms, so that the wheels will assume a slight angle with relation thereto, said angular position of the wheels causing lateral movement of the carriages and spreading 35 of the base frame arms and boom legs when the crane as a whole is moved by the tractor, means for straightening out the carriages, and other means for securing them against lateral movement when a predetermined spacing has been obtained between the carriages.

10. In a crane of the character described a base frame comprising a pair of arms pivotally connected at their front ends and adapted to be connected with and supported by the drawbar of a tractor, a wheel-supported carriage at the rear end of each arm and supporting each arm, said carriages permitting the rear ends of the arms of the base frame to be spread apart to form a base frame narrow at the front and wide at the rear, a pair of boom legs pivotally supported at their lower ends to the respective carriages, a pivotal connection between the upper ends of the boom legs, said legs adapted to be spread in unison with the frame arms to present a two-legged boom with their lower ends spread apart, and means for raising or lowering the boom legs from a horizontal trailing position to a position at right angles to the base frame arms, or to any intermediate position.

60 11. In a crane of the character described a base frame comprising a pair of arms pivotally connected at their front ends and adapted to be connected to and supported by the drawbar of a tractor, a wheel supported carriage at the rear 65 end of each arm and supporting each arm, a pivotal connection between each carriage and the arm supported thereby, means for swinging each carriage about its pivot to cause the wheels of each carriage to swing from a position parallel to the arms to a position angular thereto, whereby when the arms and carriages are pulled by the tractor the carriages will travel in a line angular to the direction of movement of the tractor and either swing the rear ends of the arms together or 70 spread them apart, a pair of boom legs pivotally

supported at their lower ends to the respective carriages, and a pivotal connection between the upper ends of the boom legs, said legs adapted to be swung toward each other or to be spread, in unison with the frame arms, to present a two-legged boom with the lower ends of the legs spread apart.

12. In a crane of the character described a base frame comprising a pair of arms pivotally connected at their front ends and adapted to be connected to and supported by the drawbar of a tractor, a wheel supported carriage at the rear end of each arm and supporting each arm, a pivotal connection between each carriage and the arm supported thereby, means for swinging each carriage about its pivot to cause the wheels of each carriage to swing from a position parallel to the arms to a position angular thereto, whereby when the arms and carriages are pulled by the tractor the carriages will travel in a line angular to the direction of movement of the tractor and either swing the rear ends of the arms together or spread them apart, a pair of boom legs pivotally supported at their lower ends to the respective carriages, a pivotal connection between the upper ends of the boom legs, said legs adapted to be swung toward each other or to be spread, in unison with the frame arms, to present a two-legged boom with the lower ends of the legs spread apart, and means for securing the legs of the boom and the arms of the base frame in their spread position.

13. In a crane of the character described a base frame comprising a pair of arms pivotally connected at their front ends and adapted to be connected to and supported by the drawbar of a tractor, a wheel supported carriage at the rear end of each arm and supporting each arm, a pivotal connection between each carriage and the arm supported thereby, means for swinging each carriage about its pivot to cause the wheels of each carriage to swing from a position parallel to the arms to a position angular thereto, whereby when the arms and carriages are pulled by the tractor the carriages will travel in a line angular to the direction of movement of the tractor and either swing the rear ends of the arms together or spread them apart, a pair of boom legs pivotally supported at their lower ends to the respective carriages, a pivotal connection between the upper ends of the boom legs, said legs adapted to be swung toward each other or to be spread, in unison with the frame arms, to present a two-legged boom with the lower ends of the legs spread apart, a second pivotal connection between the lower end of each boom leg and each carriage, and means for swinging the boom legs about said last named pivots from a horizontal position to a substantially vertical position.

14. In a crane of the character described a base frame comprising a pair of arms pivotally connected at their front ends and adapted to be connected to and supported by the drawbar of a tractor, a wheel supported carriage at the rear end of each arm and supporting each arm, a pivotal connection between each carriage and the arm supported thereby, means for swinging each carriage about its pivot to cause the wheels of each carriage to swing from a position parallel to the arms to a position angular thereto, whereby when the arms and carriages are pulled by the tractor the carriages will travel in a line angular to the direction of movement of the tractor and either swing the rear ends of the arms together or spread them apart, a pair of boom legs pivotally

boom legs pivotally supported at their lower ends to the respective carriages, a pivotal connection between the upper ends of the boom legs, said legs adapted to be swung toward each other or to be spread, in unison with the frame arms, to present a two-legged boom with the lower ends of the legs spread apart, a second pivotal connection between the lower end of each boom leg

and each carriage, means for swinging the boom legs about said last named pivots from a horizontal position to a substantially vertical position, and means for securing the boom legs and the arms of the base frame in a predetermined spread position.

HENRY D. ROGERS.
